UNITED STATES PATENT OFFICE.

CHARLES HARKNESS, OF PROVIDENCE, RHODE ISLAND, ASSIGNOR, BY MESNE ASSIGNMENTS, TO THE HARKNESS TROLLEY SYSTEM COMPANY, A CORPORATION OF RHODE ISLAND.

TROLLEY-WHEEL GUARD.

No. 868,780.

Specification of Letters Patent.

Patented Oct. 22, 1907.

Application filed February 16, 1905. Serial No. 245,854.

To all whom it may concern:

Be it known that I, CHARLES HARKNESS, a citizen of the United States, residing at Providence, in the county of Providence and State of Rhode Island, have 5 invented certain new and useful Improvements in Trolley-Wheel Guards, of which the following is a specification, reference being had therein to the accompanying drawing.

My invention relates to trolley wheel guards, and 10 has for its objects the ends commonly sought in such devices and analogous structures, including the retention of the trolley-wheel in engagement with the feed-wire while rounding curves; but more particularly to provide a guarding means available for retaining the 15 trolley-wheel in contact with the circuit-wire while traversing switches.

A further object is to provide a structure adapted to use upon a feed wire equipped with switches of varying lengths and forms; and finally, to furnish a means 20 for guiding the trolley-wheel on to the wire while leaving the switch.

My invention consists in the novel construction, arrangement and combination of parts hereinafter set forth and claimed and illustrated in the accompanying 25 drawings, wherein,

Figure 1 is an end view of a trolley equipped with my new guard. Figs. 2, 3, 4 and 5, side elevations of the same showing the successive positions of the guard in passing a switch, and Fig. 6, a side elevation of a 30 modified form of my invention.

Like reference characters indicate like parts throughout the views.

In the drawings, A is the pole, B the fork, C the spindle, and D the trolley wheel, of usual form in conjunction 35 with which my guard is employed. The latter comprises two flat oblong bars or plates, E, loosely mounted upon the spindle, C, carrying upon their upper extremities heads or disks, H², and upon their opposite ends similar members, H³. Both sets of disks 40 have convex inner faces and are provided upon their outer faces with studs, k, loosely journaled in both extremities of the bars, E. The latter are provided with an oblong opening, k', adjacent their bearings upon the spindle, C, in which is mounted a helical 45 spring, k². The openings, k', are located a little to one side of the longitudinal center of the bar E.

In the modified structure shown in Fig. 6 the disks or heads, H² and H³ are mounted upon the ends of the arms of bell crank levers, E' and E², pivotally mounted 50 on the spindle, C, whose free arms are connected by an extension spring, k³.

The operation of my device in passing a switch is shown in the drawings, wherein I represents a trolley switch, and i its flange. The normal position of each 55 bar, E, is vertical, but when a switch is reached, as

shown in Fig. 3, the head, H², rolls downwardly in contact therewith, and the bar tilts or swings or rocks, bringing the head, H³, upward. If the switch is short, the head, H³, in rising contacts with the feed wire beyond the switch. The switch, however, herein shown 60 is of considerable length, frequently found at a bridge. In this case, the rising head, H³, contacts with the bottom switch flange, as the pole, A, advances, and the head, H², rolls along the flange bottom, the parts assuming the position shown in Fig. 4. That is, the 65 bar, E, and heads are in a horizontal position, and the spring, k², is under tension. As the parts advance to the position shown in Fig. 5, the head, H³, rises, and the spring forces the head above the plane of the switch.

Similar in operation and results is the modified structure shown in Fig. 6. 70

It will be observed that my device comprises an auxiliary guarding means acting automatically in advance of the trolley wheel as the latter leaves the crossing or switch; a means which is in guarding position 75 during the entrance and departure of the wheel upon the switch; and a means which in normal position is effective while passing curves.

Having described my invention what I claim is:

1. The combination with a trolley-wheel and the spindle 80 on which said wheel is mounted, of a pair of guard plates loosely mounted upon the spindle and rotary disk shaped heads having convex inner faces mounted upon both ends of said plates.

2. The combination with a trolley-wheel and the spindle 85 on which said wheel is mounted, of a pair of guard plates loosely mounted upon the spindle, heads loosely mounted upon both ends of the plates, and spring means in the plates adjacent the spindle bearings for permitting the plates to yield vertically. 90

3. The combination with a trolley-wheel and the spindle 95 on which said wheel is mounted, of a pair of guard plates provided intermediate their length with openings pivotally mounted upon the spindle, and spiral springs mounted in said openings and bearing against the spindle. 95

4. The combination with the trolley wheel and spindle 100 on which the trolley wheel is mounted, of a pair of disconnected guard plates pivotally mounted off their centers upon the spindle, and bearing means upon both ends of the guard plates.

5. The combination with the trolley wheel and spindle 105 on which the trolley wheel is mounted, of a pair of disconnected guard plates pivotally mounted upon the spindle, and rotary disk shaped heads having convex inner faces bearing means upon the ends of the guard plates.

6. The combination with the trolley wheel and spindle 110 upon which the trolley wheel is mounted, of guard plates provided intermediate their length and off center with openings pivotally mounted on the spindle, and yielding means mounted in said openings and bearing against the spindle.

In testimony whereof I have affixed my signature in presence of two witnesses.

CHARLES HARKNESS.

Witnesses:
